J. V. YOUNG

FOLDING CHAIR

Filed Aug. 8, 1923

Patented June 28, 1927.

1,633,721

UNITED STATES PATENT OFFICE.

JAMES V. YOUNG, OF RUSHVILLE, INDIANA, ASSIGNOR TO THE STANDARD MANUFACTURING COMPANY, OF CAMBRIDGE CITY, INDIANA, A CORPORATION OF INDIANA.

FOLDING CHAIR.

Application filed August 8, 1923. Serial No. 356,398.

The object of this invention, broadly speaking, is to provide a folding chair which is simple in character, strong and durable in construction, light in weight, easily operated, will occupy but a minimum amount of space when folded, will not inadvertently tip or collapse, and which can be manufactured and sold at a comparatively low price.

More specifically stated my object is to provide a foldable chair comprising a minimum number of parts, comprising a back which is integrally connected with the front legs, having a seat pivoted at its rear portion and having rear legs rigidly connected together and which are pivoted to members of the back and so mounted that they are automatically projected back into operative position as the seat assumes substantially horizontal position and which will automatically fold in parallel with the front legs as the seat assumes its folded position parallel with the back, and to provide means whereby the seat when extended is at a higher elevation than is usual with folding chairs.

Other objects and particular advantages of the invention will suggest themselves in the course of the following description.

The preferred means for carrying out the principles of my invention in a practical and an efficient manner is shown in the accompanying drawings, in which—Figure 1 is a perspective rear view of a chair opened out and constructed in accordance with my invention. Figure 2 is an edge view of my chair in folded condition. Figure 3 is a fragmentary view, partly in section, showing the underside of a portion of the seat, and showing parts adjacent thereto. Figure 4 is a cross section of one of the rear legs, showing the sliding pivot member which is operative in connection therewith. Figure 5 is a perspective view of the sliding pivot member alone. And Figure 6 shows one of the sliding pivot members in elevation.

Similar indices denote like parts throughout the several views. In order that the construction, the arrangement, and the advantages of the invention may be more fully understood and appreciated I will now take up a detailed description thereof in which I will set forth the same as fully and as briefly as I may.

Referring now to the drawings in detail: Numerals 1 and 2 denote the two main mem-

bers, the upper portions of which form the side elements or standards of the back, and the lower portions form the front legs. Said members are identical with each other and they are perfectly straight and of the same size throughout.

The back proper comprises the cross members 3 and 4 which are spaced apart and rigidly connected to the upper portions of the members 1 and 2. Said members 3 and 4 are spaced apart parallel with each other, and they are connected by a plurality of spindles 5, which completes the back.

The members 1 and 2 are further connected by the rung 6 located near the lower ends of said members 1 and 2.

Numerals 7 and 8 denote the rear legs, whose upper ends are pivoted near the rear edges of the respective members 1 and 2 by means of the rivets 9 and 10, the same being located a short distance above the centers of the respective members 1 and 2. The outer faces of the legs 7 and 8 are in contact with the inner faces of the members 1 and 2, whereby they may be turned inward parallel therewith, as in Fig. 2 or they may be turned outward at an angle thereto, as in Fig. 1. The lower portions of the legs 7 and 8 are connected by the rung 11. Formed in the inner faces of the legs 7 and 8, and extending longitudinally thereof, are channels 12 and 13, respectively, the length of said channels depending on the limits of movement of the seat, as will hereinafter be described.

The seat comprises a frame 14, which is substantially square, and it incloses the slats 15 which fill the space between the members of the frame, however I am not to be limited to this specific construction of the seat. The width of the seat is such as to fit between the members 1 and 2, at a point a short distance below the upper ends of the legs 7 and 8, where it is pivoted on the rod 16 which extends across underneath the slats 15 and directly through the side members of the frame 14, and the end portions of said rod extend through the longitudinal central portions of the members 1 and 2, being riveted at its outer ends against the outer faces of the members 1 and 2, as shown.

A short distance rearward of the rod 16 the corner portions of the seat, that is to say, the outer rear portions of the side mem-

bers of the frame 14, are cut away forming the notches 17 and 18, whose depths are slightly more than is the thickness of the legs 7 and 8 over which they lap.

5 Two sliding pivot members are provided, each consists of a plate portion 19 having a screw aperture 20 formed through its center, to receive a screw 23. The width of said plates is substantially equal to the thickness 10 of the side members of the frame 14. Flanges 21 and 22 project inward from the respective upper and lower edges of the plates 19. Extending upward from the longitudinal center of the flanges 21 and flush 15 with the outer faces of the plates 19, are the hangers 24. And extending out from the hangers 24 is a pivot 25 which is at right angles to the plates 19, and it projects opposite to the flanges 21 and 22, all substantially 20 as shown in Figures 5 and 6. All of the parts 19, 21, 22, 24 and 25 are integral with each other.

One of said sliding pivot members is secured in each of the notches 17 and 18, with 25 the plates 19 contacting with the edges of the side members of the frame 14, and with the flanges 21 and 22 engaging the top and bottom surfaces, respectively, of the side members of the frame, and the pivots 25

30 fitting slidably in the channels 12 and 13.

Said sliding pivot members are rigidly secured to the seat, each by a screw 23, which is run through the apertures 20 and are driven into the frame 14.

35 It will now be seen that the chair may be opened out into operative condition, with the legs resting on a floor or other surface, then appearing substantially as shown in Fig. 1. In this position it is evident that 40 the pivots 25 will be at their limits of movements in the upper ends of the channels 12 and 13, which will prevent the rear end of the seat from raising, while the forward portion of the seat will be supported by 45 the rod 16, thereby preventing the seat from turning downward below horizontal position regardless of the weight placed thereon.

Now in order to fold the chair one has only to turn the seat upward, which of 50 course will force the pivots 25 downward in their channels 12 and 13, and by which as the seat reaches its upward limit parallel with and between the upper portions of the members 1 and 2 the legs 7 and 8 will automatically be forced forward causing them to enter between the lower portions of the members 1 and 2 and parallel therewith, which will cause the chair to appear as in

Fig. 2, whereby its thickness will be no greater than the width of the members 1 60 and 2, which of course will be the minimum of its collapsibility.

It will be noted that the rear legs 7-8 are pivoted to the front legs beneath the back, which back is rigidly carried by the 65 front legs. It will also be noted that the rear end of the seat extends to and between the rear legs and that the lower end of the back is spaced from said seat. There are decided advantages for this specific arrangement. In the first place, the rear legs are short and are not only stronger, but less material is necessary than if they extended above the lower end of the back and were pivoted to the upper end portions of the 70 front legs nearer. Moreover the rear end of the seat being located below and extending rearwardly beyond the back, it is thus brought rearwardly and makes a more compact structure, thereby occupying less space 75 when opened, while its entire area to its connection with the back legs is effective for use.

From the above it will be seen that the two predominant features of my chair is its maximum strength and its minimum of collapsibility.

I desire that it be understood that various changes may be made in the several details of the construction herein shown without departing from the spirit of the invention and without sacrificing any of the advantages thereof which are new and useful.

Having now fully shown and described my invention, what I claim and desire to secure by Letters Patent of the United States, is—

A folding chair comprising spaced front legs, a back fixed to and between the upper end portions of said front legs, rear legs 10 having their upper ends between the front legs and pivoted to said front legs beneath the lower end of the back, a seat extending between the front legs and pivoted between its front and rear ends to the front legs 15 below the back and below the pivotal connection of the rear legs with the front legs, the main body of said seat extending between the rear legs and having sliding interlocking connections with said rear legs, 20 said seat body when in operative position being spaced below the lower end of the back and between the rear legs.

In testimony whereof I have hereunto signed my name to this specification.

JAMES V. YOUNG.
